21 Claims. (Cl. 315—6)

1

Our invention relates to electron discharge devices and circuits therefor, particularly useful at ultra high frequencies.

For certain applications electron discharge devices must be operated as oscillators at ultra high frequencies. Under some conditions the device must also be capable of high peak power outputs for so-called pulse operation. Under these conditions of operation a number of problems are introduced, particularly where use is made of hollow conducting members referred to as resonant cavity circuits or resonators, which circuits or resonators are themselves particularly efficient at ultra high frequencies. The resonators introduce complexities in the way of tube construction in coupling the electron discharge devices to the circuits, particularly in connection with electrode supports and seals in the envelopes of such devices.

Electron discharge devices of the kind under consideration normally utilize long electron beams directed through successive resonators from a cathode to a collector normally maintained at a low voltage. Electron reflection due to space charge effects of the electrons in the beam results in undesired and uncontrolled feedback between the output and input circuits. Electron reflection also results in increased space charge and lower current, and overheating of electrodes not intended to dissipate heat, such for example as the grid. Further, the power dissipated at the collector requires efficient cooling since heating causes expansion, contraction and variation of interelectrode spacings which in turn affects the characteristics of the device. In addition this heating may severely affect the seals of the envelope made to the electrode supports and leads or to the electrodes themselves.

While the use of concentric lines and resonators for input and output circuits offers the possibility of completely shielding one circuit from the other, their use introduces the problem of providing controlled feedback energy between the circuits in proper phase relationship and further presents the problem of providing proper insulating supports which will prevent voltage breakdown across the insulators. A ready means for determining the degree of coupling and hence the amount of feedback is also a problem in this type of tube.

In order to permit circuit and electrode combinations whereby different biasing voltages may be applied to the circuits and electrodes by-passing condensers must be used which will prevent flash-over between the closely spaced electrodes

2

and circuit elements during operation and means for readily coupling the circuit elements to the tube elements must also be provided to insure rapid interchange of the electron discharge device in the apparatus when breakdown occurs.

An object of our invention is to provide an electron discharge device which is suitable for use at ultra high frequencies.

It is another object of our invention to provide an electron discharge device which is capable of pulse operation with high peak power output.

Another object of our invention is to provide an electron discharge device in which improved types of seals are utilized.

15 Another object of our invention is to provide an electrode structure whereby the interelectrode spacing may be held uniform during operation of the electron discharge device.

A further object of our invention is to provide an improved output electrode cooling system which is efficient and simple.

Another object of our invention is to provide an electron discharge device having input and output circuits particularly suitable for ultra 25 high frequencies, which are self-shielding and in which controlled coupling between the input and output electrode systems can be accomplished in proper phase relationship.

Another object of our invention is to provide 30 a tube using improved circuits of the resonator type in which tuning, adjustment and coupling are simple and easily controlled from the outside, and in which feedback control can be had without disturbing the radio frequency fields within the resonators.

Another object of our invention is to provide 35 high frequency apparatus of the type described in which the electrodes and tank circuits may be maintained at widely different D.-C. potentials with the possibility of flash-over between elements being reduced to a minimum.

A still further object of our invention is to provide 40 a mechanical coupling arrangement between the circuits and the electrodes of the electron discharge device proper which can be easily made and which will insure proper contact.

A further object of our invention is to provide 45 an apparatus for ultra high frequency use which is simple in construction, easy to assemble and in which the exposed parts for the most part are at ground potential.

Another object of our invention is to provide 50 ready means for coupling the electron discharge device with the circuit elements to insure inter-

changeability with rapidity to reduce time lost if breakdowns occur.

The novel features which we believe to be characteristic of our invention are set forth with particularity in the appended claims, but the invention itself will best be understood by reference to the following description taken in connection with the accompanying drawing in which Figure 1 is a longitudinal section of the ultra high frequency apparatus made according to our invention, Figure 2 is a section taken along the line 2—2 of Figure 1, Figure 3 is a section taken along the line 3—3 of Figure 1, Figure 4 shows details of construction of Figure 2, Figure 5 shows the details of one ring support for the cathode, Figure 6 is a longitudinal section of the electrode structure and envelope seals of the electron discharge device made according to our invention and used in the apparatus shown in Figure 1, and Figure 7 is a schematic diagram of the apparatus made according to our invention and shown in Figure 1.

Figure 1 shows an ultra high frequency apparatus incorporating our invention. The electron discharge device includes an evacuated envelope 10 having successively positioned along its longitudinal axis a cathode 11, supported on the ring 12 and grid 13 supported on ring 14, these rings being sealed through the envelope wall. The end of the envelope 10 is closed by the anode or collector 15, which projects beyond the envelope and has secured to it the cooling radiator 16, to which the anode voltage lead 17 is connected. Leads 18 provide the heating current for the indirectly heated cathode and the lead 19 is electrically connected to the cathode ring in a manner to be described.

The electron discharge device which is to be described in more detail below is incorporated in an ultra high frequency apparatus utilizing hollow conducting members or resonators which provide the input and output circuits for the apparatus.

The input circuit in the form of a coaxial line includes inner tubular member 35 and outer tubular member 36 closed at one end by the annular conducting member 37. At the open end of the inner tubular member 35 is mounted a collar-shaped member 38 provided with a plurality of outwardly flared resilient fingers 39 which contact with the cathode ring seal 12. This collar-shaped member 38 is clamped to the end of the tubular member 35 but insulated therefrom by insulating collar 40, preferably of mica. Because of this construction the cathode may be maintained at a different D.-C. potential from the input circuit and grid by means of the conductor 19 electrically connected to the collar 38 at 19'. The outer tubular member 36 is received within a U-shaped collar member 41 to which the collar member 42 is secured at 43. This gives the resilient fingers 42' a relatively long flexible length for engaging the grid ring 14. Thus there is provided between the grid and the cathode a hollow resonant conducting member totally enclosing and confining any radio frequency fields generated between the cathode and the grid.

Slidably mounted between the two tubular members 35 and 36 is the ring member 45 provided with flexible fingers 46 and 47 engaging, respectively, the inner and outer tubular members 35 and 36. This ring is initially positioned to determine the frequency range of operation of the input circuit, tuning being accomplished by means of the member 48 provided on its inner

circumference with flexible fingers 50 slidably engaging the inner tubular member 35 but spaced from the outer tubular member to permit communication between the two spaces on either side of the device for tuning. Longitudinal movement of this tuning collar or member is accomplished by means of the rod 49 extending outside the hollow conducting member or input circuit.

The output tank circuit comprises a pair of telescoping cup-shaped members 51, 52, which form together a drum-like resonator. The cup-shaped member 51 is electrically connected to and engages the U-shaped collar 41. Member 52 is provided with the collar member 60 having an L-shaped section which performs a function to be described. The cup-shaped member 52 may be telescoped within the member 51 and engagement between the two members is insured by means of flexible fingers 53 on member 52. Relative axial movement of the two members to vary the axial dimension of the resonator is accomplished by means of the structure best shown in Figures 2 and 4. Screw members 54 rotatably supported in bracket elements 55 on member 52 engage threaded brackets 56 mounted on the cup-shaped member 51. By rotating the screw members 54 and 52 may be increased or decreased to vary the output frequency of operation of the resonator.

The flange collar 60 shown in Figure 1 secured to the cup-shaped member 52 is capacity coupled to the collar 61 through insulating collar 62 preferably of mica and extending for some distance on either side of the members 60 and 61. The member 61 is provided with a plurality of flexible fingers 63 for engaging the collar 39 electrically connected to the anode and forming part of the wall of the output resonator. Thus there is provided an enclosed space between the grid and the anode which is self-shielded from the enclosed space between the cathode and the grid. Energy may be taken out of the output resonator by means of the coupling loop 65 having its opposite ends connected to the inner member 66 and outer member 67 of the coaxial transmission line. A cooling medium may be directed within the output resonator and against the seals through the ducts 68 and 69.

In order to couple the input and output circuits to control the amount of energy transferred between the circuits, we provide an adjustable coupling loop and a variable transmission line coupled between the two resonators. The transmission line connecting the input and output resonators includes a hollow conducting box-like member 70 opening into the box-like member 71 provided with spaced partition walls 72 so that a U-shaped passageway is provided within the box-like member. An elongated box-like structure 73 between the input resonator and the member 71 provides another passage through which the transmission line extends. The inner conductor of the shielded transmission line comprises tubular elements 77 and 78 in which the U-shaped member 79 slides to vary the length of these members. This U-shaped member and the slidable partition 80 positioned between the partition walls 72 are connected to and moved by rod 81, the U-shaped member 79 by means of the insulating collar 81', the conductor 81 closing the passageway. The elements 77 and 78 of the transmission line are supported within the outer conducting member by means of the insulators 82 and 83. These with the insulating collar 81' have

a dielectric constant of approximately one. We have found that insulators having a higher dielectric constant cause discontinuities in the surge impedance of the line, which in some cases results in breakdown through the insulation. By means of our construction, this breakdown is substantially eliminated.

One end of the conductor 77 is connected to the coupling loop 76 rotatably mounted on rotatable shaft 75 best shown in Figures 1 and 2. Rotation of shaft 75 increases or decreases the radius of the loop to vary coupling with the radio frequency field within the resonator. The other end of the transmission line is connected to a stub 85 of the L-shaped member 84. The member 84 has at its other end a split element 86 for engaging the inner tubular member 35, this member extending through a slot 35' in member 36. Movement of this element 84 with respect to the resonator is accomplished by means of a rod 87 to vary the point at which the connection is made to the interior of the resonator to provide the coupling desired. Thus the amount of coupling can be varied to determine the amount of energy to be fed back to the input circuit. The phase relationship between the energy fed back to the input circuit and the input voltage can be determined by the length of the transmission line and the position of member 84 within the input circuit.

In Figure 3 can be seen the details of the transmission line and the connecting element 84 with respect to the input resonator.

Details of the electrode structures and seals are shown in Figure 6. The cathode includes the collar member 20 connected to ring 12 by means of the radially directed conductors 21, the emitting portion 23 of the cathode being supported from the collar by means of the conductors 22 arranged in a circle and connected to collar 20. The heater leads 18 lie within this collar and are electrically shielded by the conductors 21 and 22 of this cathode construction and the inner tubular member 35 of the input circuit.

To insure a fixed spacing between the grid and cathode the grid is positioned with respect to the cathode by means of the insulating bead construction 26 connected to the cathode collar 20 and the apertured cup-member 24, the grid being electrically connected to the grid ring 14 by means of the L-shaped conductors 25. The member 24 and ring seal 14 provide with the input resonator a self-shielded input circuit equivalent to a solid wall hollow resonant conducting member. The grid and cathode may be assembled as a unit before being incorporated in the envelope.

In Figure 5 is shown more in detail the ring-like conducting members secured to the cathode and grid for supporting the grid and cathode and for providing a means of contact between the resonators and the electrodes within the glass envelope. The ring 12 is provided on the outside edge with a series of radially positioned slots 12' which may be enlarged at the inner end as shown and on the inside edge with slots 12''. This arrangement avoids stresses and strains in the ring due to heat absorption and thus prevents warping and strains on the seals.

The anode 15 is provided with an electron receiving surface having the same relative shape as the cathode and grid and it is found that the concave surfaces of the grid and cathode provide a more nearly fixed spacing than other forms since any contraction or expansion causes

movement of the grid and cathode in the same direction. By placing the anode close to the grid and cathode, long beams are avoided and space charge reflection is eliminated. The high anode voltages used result in considerable heating which requires means for dissipating the heat rapidly to avoid grid emission caused by the grid absorbing heat from the anode, and to keep the anode at a safe operating temperature.

In accordance with our invention we provide the anode with a cone-shaped cavity 21 within the extended portion of the anode to which the radially extending cooling fins 16 are secured. With this arrangement the large mass of anode adjacent the receiving surface absorbs and quickly transmits the heat to an effectively long and large area radiating surface, thus quickly disposing of any heat generated at the receiving surface of the anode.

To insure that the anode seal will be effectively protected during manufacture and during operation an annular depression 28 is provided having a reentrant collar 28' surrounding the depression and to which the outwardly flared collar 29 is secured, the thickness of the collar 28' and collar 29 being substantially the same to permit expansion and contraction due to variation of heating to be of the same degree so as to insure proper sealing. The end of the collar 29 is rounded to provide a proper seal in the glass envelope 10. Thus, a long path of comparatively low conductivity for heat from the receiving surface of the anode or collector to the seal is provided which offers considerably more resistance to the flow of heat than does the more solid portion of the anode through which the heat is conducted to the radiating fins 16.

A schematic longitudinal section of the apparatus made according to our invention and the associated circuits and voltage sources is shown in Figure 7. The cathode heater may be energized by means of the filament transformer 93 and the voltage to the anode may be supplied by means of the portion 90 of the circuit including a choke 45 for preventing the modulation currents from flowing through the meter. The usual protective bleeder resistors 90' are shown. The resonators are maintained at ground potential by means of conductors 91 and 92 connected to ground. 50 The input pulse or modulating signal is applied to the cathode by means of conductor 94, the resistors 95 and 96 determining the bias on the grid relative to the cathode. Normally the grid is biased to cut-off by resistors 95-96 and the 55 bias voltage neutralized by a pulse voltage being applied to the grid 13. This permits a flow of current for a short period of time between the cathode and anode. The output resonator formed of cup-shaped members 51 and 52 is thus excited and energy fed back into the input resonator by 60 means of coupling loop 76 and transmission lines 71, 77 and 78 and variable contact 84 to maintain the apparatus in oscillation. The output is taken by means of coupling loop 65 connected to the 65 transmission line 66-67.

An apparatus made according to our invention is particularly suitable for use at ultra high frequencies. It is also capable of pulse operation at high peak power outputs. The input and output circuits are particularly suitable for use at ultra high frequency and are self-shielding. The coupling between the input and output electrode systems can be substantially absolutely controlled, and feedback with proper phase is thus assured. 70 Adjustments are simple and easily controlled.

from the outside of the apparatus and feedback may be controlled without disturbing the radio frequency fields within the resonators. The construction utilized provides sure seals and yet at the same time permits the use of leads and supports which can be readily coupled to resonators. The electrode construction assures constant electrode spacing during operation of the electron discharge device and the collector construction and cooling system maintains the collector at a safe operating temperature and reduces grid heat absorption and emission. The construction used for providing capacity coupling between elements at different direct potentials and for insulatingly supporting the elements within the apparatus reduces the possibilities of flash-over and leakage. The construction utilized by our invention permits the substitution of one electron discharge device for another to be made readily and speedily. These and other objects enumerated above are attained by applicants' invention.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:

1. An electron discharge device including a cathode for supplying electrons and a collector for receiving said electrons, and a control electrode positioned between said cathode and collector, said cathode, collector and control electrode having ring-like conductors and hollow resonant conducting members provided with expandable coupling elements engaging said ring-like conductors and providing self-shielded circuits between the cathode and control electrode and between the control electrode and collector, and means for transferring energy between the hollow resonant conducting members and including a coupling loop in one of said hollow resonant conducting members and an adjustable concentric transmission line having an inner conductor, one end of which is connected to said coupling loop and its other end extending within and coupled to the inner surface of the other hollow resonant conducting member, the outer conductor of said transmission line being electrically connected to said hollow resonant conducting members.

2. An electron discharge device having a cathode, control electrode and collector all in fixed relative positions, radially directed conductors connected to said control electrode and collector and an output resonator electrically coupled between the radial conductors of the control electrode and collector and including a pair of telescoping cup-shaped members, and means for varying the relative position of said cup-shaped members to vary the natural frequency of oscillation of the resonator, said resonator having flexible finger-like elements engaging the radially directed conductors, said means for varying the relative position of said telescoping cup-shaped members including adjusting screws supported on the exterior of said telescoping cup-shaped members.

3. An electron discharge device having a cathode, control electrode and collector, said control

electrode and collector having ring-like conductors and an output resonator electrically coupled between the ring-like conductors and including a pair of telescoping cup-shaped members, and means on said resonator for varying the relative position of said cup-shaped members to vary the natural frequency of oscillation of the resonator, one of said cup-shaped members having flexible finger-like elements engaging one of said ring-like conductors, the other of said cup-shaped members having an annular member, a second annular member within the first mentioned annular member and capacitively coupled thereto and having flexible fingers engaging the other ring-like conductor.

4. An electron discharge device having a cathode, control electrode and collector, said control electrode and collector having ring-like conductors and an output resonator electrically coupled between the ring-like conductors, one portion of said resonator having flexible finger-like elements engaging one of said ring-like conductors, another portion of said resonator having a first annular member, a second annular member within said first annular member and capacitively coupled to said first annular member and having fingers engaging the other ring-like conductor, whereby the space between the ring-like conductors communicates with the interior of said resonator.

5. An electron discharge device having a cathode, and an anode, said anode comprising an elongated hollow member defining a cavity there-within and having a closed end for receiving electrons and an open end being open to the exterior of said device, said closed end being closest to said cathode, the cavity within said hollow member extending from the open end thereof and of decreasing proportions toward said closed end and radiating fins positioned transversely of and successively along said anode from the open end toward the closed end.

6. An electron discharge device having an envelope containing a cathode, and an anode, said anode comprising an elongated hollow member, one end of which is closed and oppositely disposed to said cathode within said envelope to receive electrons from the cathode the cavity within said anode extending from the open end thereof and of decreasing proportions toward the end for receiving electrons, and heat radiating means positioned on said anode, said cavity being open to the exterior of the envelope.

7. An electron discharge device having a cathode, control electrode and anode, said cathode, control electrode and anode having registering concave surfaces spaced from each other, said anode comprising an elongated member having its concave end positioned to receive electrons from said cathode and having a cone-like cavity extending from the other end thereof with the tip of the cone toward the concave end for receiving electrons, and heat radiating fins positioned transversely of and successively along said anode.

8. An electron discharge device having an envelope containing a cathode, and an anode, said anode being elongated and having one end within said envelope and oppositely disposed to said cathode to receive electrons from said cathode and having a cone-like cavity extending from the other end thereof with the tip of the cone toward the end for receiving electrons, and a collar member electrically connected to and supported on said anode intermediate the ends of

the anode, said collar member extending along the anode but spaced therefrom and having the free edge of said collar sealed to one end of said envelope, and heat radiating means positioned in said anode outside of said envelope.

9. An electron discharge device having an envelope containing a cathode, grid and an anode, said anode being elongated and having one end within said envelope and oppositely disposed to said cathode to receive electrons from said cathode, and having a cone-like cavity extending from the other end thereof with the tip of the cone toward the end of the anode for receiving electrons, the receiving end of said anode being of smaller cross section than the remainder of said anode, and an annular lip on said anode extending around and along the anode and having one edge spaced from said anode and extending toward the receiving end of said anode, an outwardly flared collar member having one end secured to said lip and the other end sealed to said envelope closing the end of said envelope, and heat radiating fins extending transversely of the anode and positioned successively along the anode outside of said envelope.

10. An electron discharge device having a cathode provided with a ring-like supporting element, and an anode, said anode being elongated and having one end within said envelope and oppositely disposed to said cathode to provide a surface for receiving electrons from the cathode, said anode having a cone-like cavity extending from the other end thereof with the tip of the cone toward the end for receiving electrons, and a collar member having one end secured to the anode intermediate the ends of said anode and flaring outwardly toward the receiving end of the anode, and insulating material connected between the ring-like member of said cathode and the free end of said collar member providing an envelope for said cathode and said anode, and heat radiating fins connected to said anode exteriorly of the envelope of said tube.

11. An electron discharge device including an envelope having a cathode, grid electrode and an anode, said cathode and grid electrode including a pair of nested cup-like elements insulatingly supported from each other and having radially directed supporting elements, ring-like supporting elements coaxial with said cathode and grid electrode and electrically connected to said radially directed supporting elements and sealed through the wall of said envelope, said anode having a collar member, one edge of which is connected to the anode and the other edge of which is sealed to the end of the envelope providing an enclosure for said cathode, grid electrode and anode.

12. An electron discharge device having a cathode, grid and anode, said cathode and grid being provided with coaxial ring-like conducting members supporting said cathode and grid, and a collar on said anode coaxial with said ring-like members, an input circuit including a coaxial line resonator, the inner conductor of said resonator being provided with longitudinally extending flexible conducting fingers engaging the periphery of the cathode ring-like member, and the outer conductor of said resonator being provided with other longitudinally extending flexible conducting fingers engaging the periphery of the grid ring-like member, whereby the space between the cathode and grid communicates with the interior of said resonator, and a resonator coupled between said first resonator and said

anode and having a plurality of longitudinally extending flexible fingers electrically contacting the periphery of said collar.

13. An electron discharge device having a cathode, grid and anode, said cathode and grid being provided with coaxial ring-like conducting members supporting said cathode and grid, and a collar on said anode coaxial with said ring-like members, a coaxial line resonator, the inner conductor of said resonator being provided with longitudinally extending flexible conducting fingers engaging the periphery of the cathode ring-like member, and the outer conductor of said resonator having longitudinally extending flexible conducting fingers engaging the periphery of the grid ring-like member, whereby the space between the cathode and grid communicates with the interior of said resonator, and a resonator coupled between said first resonator and said anode and having a plurality of longitudinally extending flexible fingers electrically contacting said collar, and a coaxial transmission line coupling the resonators.

14. An electron discharge device having a cathode, grid and anode, said cathode and grid being provided with coaxial ring-like conducting members supporting said grid and cathode, an input coaxial line resonator, the inner conductor of said resonator having flexible conducting fingers engaging the cathode ring-like member, and the outer conductor of said resonator having flexible conducting fingers engaging the grid ring-like member, whereby the space between the cathode and grid communicates with the interior of said resonator, and a second resonator coupled between said first resonator and said anode, and a coaxial transmission line coupling the resonators together, a coupling loop within said second resonator and connected to one end of said line, and a contact member connected to the other end of said line, said contact member being movable along and contacting the inner surface of the inner conductor of the input resonator.

15. An electron discharge device having an envelope containing a plurality of electrodes and a ring-like supporting element extending through said envelope and electrically connected to one of said electrodes, said ring-like member being sealed through the wall of the envelope of the tube and having radial slots therein extending from an edge of said ring-like member.

16. An electron discharge device having an envelope containing a plurality of electrodes and a ring-like supporting element extending through said envelope and electrically connected to one of said electrodes, said ring-like member being sealed to the wall of the envelope and having a plurality of radial slots therein extending from opposite edges thereof.

17. An electron discharge device having an envelope containing a plurality of electrodes and a ring-like supporting element extending through said envelope and electrically connected to one of said electrodes, said ring-like member being sealed to the wall of the envelope and having radial slots therein extending from the outer edge toward the inner edge of said ring-like member exteriorly of the envelope and being enlarged at their inner ends.

18. An electron discharge having a cathode, control electrode and anode, a first resonator connected between said cathode and control electrode, and a second resonator connected between said control electrode and anode, and a coaxial transmission line connected between said reso-

nators, one end of said coaxial transmission line extending within said first resonator and a coupling loop within said second resonator connected to the other end of said transmission line, said coupling loop including an arcuate-shaped flexible member and means connected to said arcuate-shaped flexible member for changing the radius of curvature of said flexible member to vary the coupling of said loop with said second resonator.

19. An electron discharge device having a cathode, control electrode and anode, a resonator connected between said cathode and control electrode, and a second resonator connected between said control electrode and said anode, an adjustable coaxial transmission line coupled between said resonator and including an elongated tubular structure having a longitudinally adjustable partition providing a pair of adjacent passageways of adjustable length communicating at one end and an inner conducting member supported within said passageways and adjustable with said partition to change the length of said transmission line, and a coupling loop connected to one end of said transmission line and within one of said resonators, and a tap connected to the other end of said transmission line and extending within the other resonator.

20. An electron discharge device having a cathode, control electrode and anode, a first resonator connected between said cathode and control electrode, and a second resonator connected between said control electrode and said anode, and a coaxial transmission line connected between said resonators and including an elongated tubular structure, a partition extending along said tubular structure providing a pair of adjacent parallel chambers having a communicating passageway at one end, a tubular member within each of said chambers and extending longitudinally of said chambers but out of contact with the tubular structure and a U-shaped element telescopically engaging and connecting said tubular members and extending through said communicating passageway, a partition extension, said partition extension and said U-shaped member being movable as a unit to vary the length of the coaxial transmission line, a coupling loop within said second resonator and connected to one of said tubular members, and a contact member within the first resonator and connected to the other tubular member.

21. An electron discharge device having a cathode, control electrode and anode, a first reso-

nator connected between said cathode and control electrode, and a second resonator connected between said control electrode and said anode, and a coaxial transmission line coupling said resonators and including an elongated tubular conducting structure, a partition within said structure dividing the tubular structure into two chambers having a communicating passage at one end and comprising a pair of closely spaced elements, a first member positioned longitudinally of and out of contact with the walls of one of the chambers and a second member positioned longitudinally of and spaced from the walls of the other chamber, a U-shaped member having its ends telescopically engaged with said members and slideable with respect to said members, an elongated member slidably engaged between the spaced partition elements for extending the length of said partition within the tubular structure and movable means closing one end of said tubular structure adjacent the U-shaped element, said closure member, U-shaped member and slideable elongated member being movable as a unit longitudinally of the tubular structure to vary the length of the transmission line, one of said tubular elements being electrically connected to the interior of the first resonator and the other tubular member being coupled to said second resonator.
